GUY O. LEAR, OF KUNA, IDAHO.

WATER-WHEEL.

1,293,480.

Specification of Letters Patent.

Patented Feb. 4, 1919.

Application filed December 19, 1917. Serial No. 207,947.

To all whom it may concern:

Be it known that I, GUY O. LEAR, citizen of the United States, residing at Kuna, in the county of Ada and State of Idaho, have 5 invented certain new and useful Improvements in Water-Wheels, of which the following is a specification.

This invention is a water wheel and has for its principal object the production of a 10 device which is adapted to force water to various points desired thus facilitating the elevating of the water or the carrying of the water to various places, thus being particularly adapted for irrigating purposes.

15 Another object of this invention is the production of a pumping structure which receives water from a stream the device also being provided with a wheel to be operated by the force of the current, thus allowing 20 the device to operate without cost after the initial installation.

Another object of this invention is the production of a pumping structure which has a housing connected at one end to a 25 tubular chamber, this chamber being provided with a check-valve so as to permit water to be passed from the housing into the tubular chamber and thus permit the spiral member within the tubular chamber to force 30 the water therefrom into a suitable conveying means.

Another object of this invention is the production of a pumping structure which has the power wheel journaled upon the 35 housing, thus permitting the shaft of the spiral member to receive rotary motion from suitable gears, whereby as the power wheel rotates the spiral will also be rotated for forcing water from the tubular chamber, it being, of course, obvious that a pressure 40 of the water from the stream and within the housing will be sufficient to pass into the tubular chamber and supply the tubular chamber with the necessary water for 45 insuring proper operation of the spiral member.

With these and other objects in view this invention consists of certain novel combination, construction, and arrangement of parts 50 as will be hereinafter fully described and claimed.

One practical form of construction and assembly of the present invention will be hereinafter described in the accompanying 55 drawings, in which:

Figure 1 is a longitudinal section through the housing and tubular chamber, the power wheel, spiral member and connecting elements being illustrated in elevation.

Fig. 2 is a section taken on the line 2—2 60 of Fig. 1, looking in the direction of the arrow.

Fig. 3 is a section taken on the line 3—3 65 of Fig. 1, looking in the direction of the arrow.

Referring to the accompanying drawing by numerals, it will be seen that the device is used in general in connection with a stream, indicated in general at 1, and adjacent the usual bank 2.

The housing 3 may be of any desired 70 shape and is provided with a closed inner end 4 having a flange 5. This housing 3 is provided with an open front end, as illustrated clearly in Fig. 2. This housing is 75 carried preferably by the bank 2 at a point below the water line of the stream 1, thus causing the housing to be normally filled with water from the stream.

The tubular chamber 6 is provided with 80 a closed end 7 projecting into the housing 3, the annular flange 5 of the closed end 4 of the housing 3 bearing upon this tubular chamber, as illustrated in Figs. 1 and 3. In order to permit water to pass from the housing 3 into the tubular chamber 6, the chamber is provided in its closed end 7 with a plurality of check valves 8. These check valves 8 are of any suitable construction, as it is only desired to provide some suitable form 90 which will permit the water to pass from the housing into the tubular member, although preventing the water from repassing from the tubular member into the housing, in the event the water line of the stream 95 should for some reason fall below the center of the housing. The conduit 9 leads from the opened end of the tubular chamber 6, as indicated in Fig. 1 and may extend to wherever it is desired to convey the water. 100

The spiral member shaft 10 is journaled in the closed end 7 of the tubular member 6 and has one end journaled in the brackets 11 fixedly secured in the outer end portion of the tubular member 6. The spiral member 105 12 is secured in any suitable manner to the shaft 10 and is carried within the tubular member 6. It is therefore obvious that as rotary motion is imparted by the shaft 10 to the spiral member 12, this spiral member 110

will be driven at a sufficient rate of speed as will cause the water to be driven from the tubular member into the conduit 9.

A vertical bracket 13 having angularly 5 extending feet 14 is permanently carried within the housing 3 at a point adjacent the outer opened end thereof as indicated clearly in Figs. 1 and 2. This bracket 13 is provided with a bearing portion 15 adjacent its center 10 and the remaining end portion of the shaft 10 is journaled in this bearing 15. Thus it will be seen that the shaft 10 is supported at points adjacent its ends and also intermediate its ends and in this way is permanently 15 supported. The reduced pinion 16 is fixed or keyed in any suitable manner upon the shaft 10 at a point adjacent the bearing 15, for purposes to be hereinafter set forth.

A bracket arm 17 which is preferably of 20 an L shaped construction has its horizontal portion fixed in any suitable manner to the lower portion of the housing 3. The vertical portion of the L shaped arm 17 is provided with a bearing 20 and the driving shaft 21 25 passes through the bearing 20, as shown in Fig. 1. This driving shaft 21 has its inner end journaled in the bearing member 22 carried upon the bracket 13 at a point intermediate the lower end of this bracket and 30 the bearing 15. An enlarged gear 23 is fixed or keyed in any suitable manner upon the driving shaft 21 at a point adjacent the inner end thereof and this gear 23 is at all 35 times in meshing engagement with the reduced pinion 16. Thus it is obvious that as rotary motion is imparted to the driving shaft 21 it will in turn be imparted through the gear 23 and pinion 16 to the shaft 10. It is of course obvious that owing to the relative size of the gear 23, when taking into 40 consideration the size of the pinion 16, the speed of the shaft 10 will be increased over the speed of the rotating driving shaft 21.

The driving wheel comprises a base 24 45 having webs 25 affixed thereon in any suitable manner. It is of course obvious that any form of a driving wheel desired may be employed in connection with the present device and the one herein shown is only illustrated to disclose the driving means for the pumping structure. This driving wheel is carried at a considerable distance from the housing 3 to receive the force of impact of the water caused by the current of the stream. This force will cause the driving wheel to rotate at a comparatively rapid speed, or in accordance with the movement 55 of the stream, and as the driving wheel is positioned below the water line, it is obvious 60 it will continually rotate as long as it is submerged and in this way will considerably increase the capacity of the pumping structure.

When this device is in operation, the conduit is conducted to a suitable location while 65 the housing and driving wheel are mounted

in the manner hereinbefore specified. As the force of the current of the stream will cause the drive wheel to rotate, it is obvious the driving shaft 21 will also be rotated. The rotation of this driving shaft will impart the rotary movement to the gear 23 and the movement of the gear will impart motion to the pinion 16 at an increased rate of speed. As the pinion is keyed upon the shaft 10, it is obvious the shaft 10 will be rapidly rotated and will in this way cause the spiral member to be rotated with considerable speed. This movement of the spiral member will cause the water to be moved therefrom and driven into the conduit. The pressure 80 of the water in the stream and housing will of course force the water through the check valves 8 into the tubular member to supply the tubular member with a continuous flow for insuring the proper supply of water for 85 causing the spiral member to pump an even or uniform flow of water therefrom into the conduit.

As above specified, this device after being installed will operate without expense and 90 owing to the fact that it is submerged it will continuously operate and for this reason is capable of elevating water to a considerable height or forcing the same for a considerable distance at a slight incline or on a level and 95 for this reason it is well adapted for inexpensive irrigating purposes. It is of course obvious that it may be employed for other purposes than irrigation, since its utility in connection with irrigation has been mentioned as merely disclosing the utility of the pumping structure.

As only one form of the present invention has been herein illustrated, it is obvious that minor changes in detail construction of the 105 invention may be made, as long as these changes do not exceed the scope of the invention as claimed:

What is claimed is:—

1. In a device of the class described, the combination of a housing, a tubular member projecting into said housing, a spiral member carried within said tubular member, said housing having an open end, said housing being adapted to be carried below the water line of a stream, whereby the water will pass into said housing and then into said tubular member, and means carried by said housing for imparting rotary motion to said spiral member, thus causing the water with 115 in said tubular member to be forced therefrom.

2. In a device of the class described, the combination of a housing, said housing having a closed inner end and an open outer end, a tubular member projecting into said housing through said closed inner end, check valves carried by said tubular member; said housing being adapted to be carried below the water line of a stream, thus allowing a 125

water pressure within the housing for causing the water to pass through said valves into said tubular member, said valves preventing the passing of water from said tubular member back into said housing, a spiral member carried within said tubular member, and means carried by said housing for imparting rotary motion to said spiral member, thus causing the spiral member to force water from said tubular member.

3. In a device of the class described, the combination of a tubular member, said tubular member having a closed end, check valves carried by the closed end of said tubular member, a housing having a closed end and an open end, said tubular member projecting through the closed end of said housing and into the interior thereof, said housing being adapted to be carried below the water line of a stream for maintaining a water pressure within said housing, thus causing the water to pass through said valves into said tubular member, although said valves will prevent the repassing of the water from said tubular member back into said housing, pump means carried within said tubular member, and driving means carried by said housing, for operating said pump means and thus force water from said tubular member.

4. In a device of the class described, the combination of a housing, an L shaped bracket arm fixed to said housing and projecting for a considerable distance therebeyond, a driving shaft journaled upon said bracket arm, a driving wheel connected to said shaft, said driving wheel being adapted to be driven by water power, a tubular member connected to said housing, a pumping means arranged within said tubular member and means connecting said pumping means to said driving shaft, thus causing said driving shaft to operate said pumping means for forcing water from said tubular member.

45 5. In a device of the class described, the combination of a housing, a tubular member projecting into said housing, check valves carried by said tubular member, a shaft journaled upon said housing and tubular

member a spiral member connected to said shaft and positioned within said tubular member, a bracket arm mounted upon said housing, a driving shaft journaled upon said bracket arm, a driving wheel connected to said shaft, a gear fixed upon said driving shaft, a pinion fixed upon said first mentioned shaft and meshing with said gear, whereby as said driving wheel rotates said driving shaft rotary motion will be imparted to said gear and then by said pinion to said first mentioned shaft, thus allowing said first mentioned shaft to operate said spiral member for forcing water from said tubular member.

6. In a device of the class described, the combination of a housing having a closed end and an open end, a bracket carried within the open end of said housing, a tubular member projecting through the closed end of said housing, check valves carried by said tubular member, a bracket carried by said tubular member, a shaft projecting through said tubular member and having its ends journaled upon said brackets, a pumping means connected to said shaft, an L shaped bracket arm mounted upon said housing, a driving shaft journaled upon said bracket arm and said first mentioned bracket, a gear fixed upon said driving shaft, a pinion fixed upon said first mentioned shaft and meshing with said gear, and a driving wheel fixed upon said driving shaft, whereby the device may be submerged in a stream to allow water to pass through said housing and valves into said tubular member, and said driving wheel being adapted to be rotated by the movement of the stream, thus causing rotary motion to be imparted to said driving shaft and gear to said pinion and first mentioned shaft, thus causing said first mentioned shaft to operate said pumping means for forcing water from said tubular member.

In testimony whereof I affix my signature in presence of a witness.

GUY O. LEAR.
